2 SHEETS-SHEET 2.

UNITED STATES PATENT OFFICE.

JUDSON McFELL, OF CHICAGO, ILLINOIS.

SELECTIVE SIGNALING SYSTEM.

1,076,303.

Specification of Letters Patent.

Patented Oct. 21, 1913.

Application filed April 19, 1910. Serial No. 556,403.

To all whom it may concern:

Be it known that I, JUDSON McFELL, a citizen of the United States, residing at Chicago, in the county of Cook and State 5 of Illinois, have invented certain new and useful Improvements in Selective Signaling Systems, of which the following is a specification.

My invention relates to improvements in 10 selective signaling systems and has for its general object to provide means whereby a selector device at any one of a plurality of signal receiving stations upon a line may selectively be caused to condition for operation the annunciator at such station by transmission over the line wire of groups of signal impulses constituting a plural-digit number-signal appropriate to said station.

A further object of my invention is to 20 provide a system and apparatus wherein the selector at each station embodies only a single step-up device, responsive to the line condition, arranged and operating to advance in groups of steps in accordance with 25 the groups of impulses constituting number digits in the code signal transmitted, and arranged to condition its annunciator for operation only when such step-groups of the step-up part correspond with the code number 30 appropriate to that station for which the selector is set.

Another object of my invention is to provide a system which will be simple, effective, and cheap, and will enable intercommunication to be had between the various 35 stations on the line, if desired.

Other and further objects of my invention will become apparent from the following description taken in conjunction with the accompanying 40 drawings, wherein—

Figure 1 is a front elevation of a selector device, shown schematically as connected as part of a signaling system; Fig. 2 is a rear elevation of some of the parts of the selector; Fig. 3 is a plan view of the selector; Fig. 4 is a detail.

In the drawings, 10—10', indicate line wires, constituting a metallic circuit, provided with a suitable source of current supply, 11, and having connected therewith the selector apparatus of a plurality of stations, as A and B, the apparatus of station A, only, being indicated in detail.

At each station from which signals are to 55 be sent,—say, from the station of a train despatcher,—there is provided a signal

transmitter, 12, for operation to effect the continuity of the circuit to send groups of signaling impulses, constituting digits of number signals, thereby to affect an electro-responsive device at each signal-receiving station, and to cause the operation of the primary step-up part of the selector devices. By impulses, as the term is herein employed, I mean such impulsive changes of the line 60 condition as may be utilized to actuate appropriate electro-responsive devices, such as electromagnets, and in the specific construction shown, such signaling impulses are caused by closing of a normally open line. 65 For the disclosure of one operative embodiment of my invention, I show apparatus adapted for an open circuit despatcher's system, but it will be understood that in its 70 broader aspects my invention is not limited to such arrangement. Thus, 14 indicates a normally open line-closing switch, preferably having associated therewith a normally-open grounding switch, 15, for one side, as 10, of the line. 16 is a signaling 75 wheel, having notches, 17, cut in its periphery, standing normally with a terminal arc, 18, opening the switch, 14, so that by revolution of the wheel the signaling switch may close upon passage of such wheel notch 80 therewith. In practice such signaling wheel or wheels would generally be motor-driven, but I herein indicate for simplicity the wheel as driven by a hand crank, 19, stoppage in a predetermined proper position being effected by the spring 19', bearing 85 against the notched disk, 20, on the crank shaft.

For enabling the transmitter to operate to transmit predetermined code signals, each 90 consisting of a group of digits with each digit group followed by a closing of the ground switch, 15, I provide means upon the wheel, 16, whereby certain of the notches may be closed by clips adapted to cause the 95 closure of the ground switch, 15. Schematically, I have shown, in Figs. 1 and 4, the wheel provided with movable clips, 21, each capable of being placed in any notch desired, and each arranged when in place to 100 close the notch in the signaling wheel, and to provide a crest, 22, projecting beyond the wheel periphery for raising the signaling switch, 14, upward so as to close the ground switch, 15, connected therewith, to ground 105 one side of the battery 11, through wire 10. Also I provide on the wheel, just in advance 110

of the terminal arc, 18, a permanent tooth, 18', for closing the grounding switch. Thus, as indicated in Fig. 1, the wheel has its clips, 21, so spaced that four notches are free, then one notch closed, by a clip, then six are free, another clip closes the succeeding notch, and then three notches are free, followed by a clip closing the next notch, the remaining notches in the periphery of the circle being all free until tooth 18' is reached. This conditions the wheel to send the signal 463, followed by a series of "arbitrary" impulses which bring the total number of impulses up to some predetermined quantity, and then to close the grounding switch, 15, just before the wheel comes to rest.

At each signal-responsive station, the line has operatively associated therewith a current-responsive device, 25, such as an electromagnet, preferably bridged between line wires 10 and 10', so as normally to be deenergized and to attract its armature 26, against the tension of spring 27 whenever it is energized. The armature, 26, is provided with a lever arm, 26', bearing at its upper end a pawl, 28, riding over a pin, 29, projecting from the metal base plate of the selector apparatus, and pressed downward by a spring, 30, so that the nose of said pawl stands normally out of engagement with, but upon advance movement may engage, a spring-returnable ratchet wheel, 31, whereof 31' is the spring constituting the primary step-up part of the selector, and provided with a suitable holding pawl, 33. This step-up part through the action of the impulse-responsive magnet, 25, is made to advance in step groups in harmony with the impulse groups occasioned by the operation of the signal transmitter, 12, and, as hereafter described, it controls the annunciator and its actuating mechanism, the ratchet wheel, 31, with its connected parts constituting a primary controlling means by which is controlled the movable element of a secondary controller, to be described.

In the installation of the system shown, the annunciator is an electric bell, 35, connected on one side by wire, 36, with wire, 10', of the main circuit, and at its other side connected with the stationary contact, 37, of a switch, the movable contact of which is part of a connection 37', extending to binding post 38 and thence by wire 38' to line wire 10. The switch closing arm 37'' is connected with a ratchet wheel 39 mounted on a shaft 40 in a suitable bracket 41 carried by the base plate 24. This ratchet may be given step-by-step movement toward closing position and is automatically spring-returned to open position upon release from restraint. For moving the ratchet forward I provide another pawl, 42, mounted upon an armature lever, 43, nor-

mally pressed into engagement with its ratchet by a suitable spring, 44', a holding pawl, 45', being suitably pivoted in the frame to retain the ratchet against spring return by its spring 39' as it is moved forward step by step by the active pawl, 42. The armature lever, 43, carries the armature, 44, of an electromagnet, 45, and said lever is normally retracted by a spring, 46. The magnet, 45, constitutes the actuating device of a secondary controller (comprising in the present instance, ratchet wheel, 39, and its connected parts) which may, by a plurality of successive steps or movements, condition the annunciator for operation.

To the end that the secondary controlling device shall be controlled by the primary controlling device, and conditioned for operation only when the latter dwells in predetermined positions, I preferably arrange the coil of the magnet, 45, in a circuit grounded at one side, as by wire 50, and having its other terminal connected, as by wire, 51, in multiple with a series of stationary contacts, 52, 53, and 54, carried by and insulated from the bracket, 55, for the shaft of ratchet, 31, said stationary contacts coöperating with a contact point, 56, upon the ratchet wheel, 31, which has electrical connection through the framework, binding post, 38, and wire 38', with the side 10 of the line. Now, in general it will be seen that whenever the ratchet 31 is so located that the contact point 56 stands beneath contact point 52, connection is made from the side 10 of the line, by wire 38', binding post 38, metallic frame, ratchet 31, point 56, stationary contact, 52, wire 51, electromagnet 45, and wire 50 to ground, so that, if the line 10, is grounded at the time this condition prevails in the selector apparatus, the magnet 45 will be energized by the grounded circuit including battery 11. Such grounding of the side 10' of the line will, however, occur only if the movable clip 21 of the signaling wheel corresponds in position with the setting of contact point, 52, that is to say, in the specific arrangement shown in Fig. 1, assuming the contact point 52 to stand four steps in advance of the initial position of contact, 56, the transmission of a group of four impulses constituting the first digit of a number signal will cause the advance of ratchet, 31, four steps to bring the point, 56, into engagement with the contact, 52, and then the closing of the grounding switch 15 by the operation of the clip, 21 will cause the grounding of the side 10' of the line and complete the circuit for the secondary magnet, 45, so causing said magnet to become energized and to attract its armature 44, and thereby advancing the secondary step-up device, 39, one step. Thus, it will be apparent that in order for the selector at any station to step up the secondary ratchet, 39, 130

three steps, thereby to condition the annunciator for operation, in response to the three digits of the number signal transmitted by a signaling wheel, 16, the stationary contacts, 52, 53, and 54, of said selector must be set at intervals corresponding to the digits of the number. For general utility, I find that a three digit number signal is advantageous, although obviously by addition or subtraction of stationary contact points for the primary step-up device and a corresponding setting of the contact, 37, with relation to the secondary step-up device, the apparatus might be made to operate upon number signals consisting of any desired number of digits.

I prefer that the selector shall be mechanically self-restoring to initial condition at the termination of a signaling operation, 20 and to this end, I preferably provide a mechanical construction such as I will now describe. The holding pawl, 33, for the ratchet 31 is provided with an arm, 60, which when moved to the left (Fig. 2) raises 25 the pawl out of engagement with the ratchet, and it is likewise provided with a latching arm, 61, adapted to be engaged by a gravity latch, 62, suitably pivoted in the frame and subject to movement to unlatching position 30 by a pin, 63, upon the ratchet 31. For disabling the holding pawl, 33, I provide a link, 65, pivoted to the armature lever, 43, of the secondary magnet, normally guided upon a pin, 66, secured to the frame, and 35 provided with a hook, 67, normally riding below the extremity of the arm, 60. Upon the rear face of the ratchet wheel, 31, I provide a cam, 68, adapted to raise the link, 65, and afford support to the forward end 40 thereof in such manner as to bring the hook 67 up to position to engage the arm 60 of the holding pawl, 33, the cam, 68, being so located upon the wheel that its time of engagement with the link is subsequent to the 45 completion of the transmission of any signaling number which the system is adapted to encompass. That is to say, assuming for example that 666 be the highest number that the system takes care of, it should require 50 more than 18 impulses to bring the cam 68 into operative relation to the link, 65.

For releasing the holding pawl, 45', of the secondary ratchet, I provide a trigger, 70, pivotally mounted on the rear face of the 55 ratchet, 31, and pressed in one direction against the stop 71 by a light spring 72, so that during the advance movement of the ratchet, 31, said trigger may pass the extremity of the holding pawl, 45, and on its 60 return movement may trip said pawl, 45, to ratchet-releasing position.

Whenever the live pawl, 28, for ratchet 31, stands retracted it is out of engagement with its wheel, 31, and therefore exerts no 65 holding influence, and no mechanism is re-

quired to take care of this part. A disabling lever, 75, is, however, preferably provided for the live pawl, 42, of the secondary ratchet, this lever being pivoted upon a pin, 76, projecting from the plate and having 70 one end arranged to receive a cam, 77, projecting from the ratchet wheel 31, thereby to lift the live pawl 42 of the secondary ratchet to disabled position at about the time when cam 68 coacts with link 65.

For conditioning the magnet 45 to receive an impulse to effect the releasing operation, I further provide upon the wheel a cam, 80, arranged to contact with a spring, 81, connected with wire 51, just after the cam 68 cooperates with the link 65, said cam 80 serving to connect the wire 51 and the binding post 38, to the spring 81, and the metallic parts of the selector. Further to insure good electrical connection under these conditions, I provide a spring, 82, connected by clip 83 with the metallic parts of the selector, arranged to contact with the spring 81 when the latter is acted upon by the cam member 80, so that connection of the wire 51 to the frame work and its binding post, 38, is made not only through the sliding contact 80—81, but also between the spring contacts 81—82. Now, it will be apparent that in the sequence of operation, 85 the releasing devices work as follows: After all the impulses of the digits have been received, the arbitrary impulses cause further advance of the ratchet, 31. During this interval of arbitrary operation, cam 68 raises 90 link 65 to functionally operative position, trigger, 70, passes the tail of holding pawl, 45, of the secondary ratchet, and cam 77 moves the lever, 75, to lift to disabled 95 position the live pawl 42 of the secondary ratchet. Subsequently, the cam 80 makes 100 its connection with spring, 81, closing the selector end of the grounded circuit for magnet 45. Now, when the ground circuit of magnet 45 is completed by the passage 105 of the high point 18' of the signaling wheel under the grounding switch, 15, grounding the line 10' through said switch 15, magnet 45 attracts its armature 44, pulling over the link 65, and throwing the holding pawl 33 for the primary ratchet to disabled position where it is locked by the latch 62, so that the ratchet 31 may start back under spring pressure to initial position. In the course 110 of this return movement, trigger 70 trips the holding pawl for the secondary ratchet enabling it to return under its spring influence to initial position, and finally the pin 63 trips the latch 62 and allows the holding pawl 33 for the primary ratchet to return to operative position just as the primary ratchet 31 comes to its initial or terminal position.

In brief resume of the operation of the system, it will be seen that every closure of 130

the line circuit, energizing magnet 25, causes the active pawl, 28, to advance the primary ratchet, 31, one step, so that the ratchet wheel of the primary controlling devices at all stations will advance and dwell in response to the number digits of the signal sent over the line. At the completion of each number digit, one side of the line is grounded and at each station where, 5 at such time, point 56 of the primary ratchet stands under a stationary contact, a ground circuit is completed through the secondary magnet 45 of that selector, so that the operation of the secondary controller 10 is governed by the rotation of mechanism appurtenant to the primary controller. Each time the secondary magnet is energized it steps forward the secondary ratchet, 39, one step, it being necessary to step the 15 secondary ratchet forward as many steps as there are digits in the number signal in order that the annunciator 35 shall have its circuit closed and be thereby conditioned for operation, so that as to each of its plurality of movements necessary to condition the annunciator for operation said secondary controller is controlled by the condition of the primary controller. Obviously, 20 when a three digit number is transmitted, say the number 463, only those selectors 25 having the first contact finger 52 four steps from the terminal position will have their secondary magnets energized when the first clip 21 occasions the switch 15 to ground 30 the line; only those selectors having the second contact 53 ten steps removed from terminal position will correspondingly have their magnets 45 grounded on the second closure of the circuit; and only those 35 selectors having the third contact 54 thirteen steps removed from the terminal position will have their magnets 45 respond to the third closure of the ground circuit; and the selector at station 463, being the only one 40 with contacts corresponding with all three of these points, will be the only one to have its secondary ratchet advanced three steps, or sufficiently to close the annunciator circuit. After the signaling digits have been 45 transmitted, an arbitrary number of succeeding impulses occur in the line, and during such period of arbitrary operation, first the cam 68 lifts the link 65, causing hook 67, to engage the arm 60 of the holding 50 pawl 33, trigger 71 passes holding pawl, 45', and cam, 77, actuates pivoted lever, 75, which lifts or disables the actuating pawl, 42, for the secondary ratchet; and then, 55 cam 80 makes contact with spring 81 forcing the latter into contact with spring 82, so that when the high point 18' of the signaling wheel occasions the closure of the ground switch just before the wheel comes to rest, 60 a grounded circuit is completed from ground through the switch 15, wire 12, bat-

tery 11, wire 10, wire 38', the metallic frame of the selector, to cam 80, the spring 81, wire 51, magnet coil, 45, and wire 50, to ground, so that coil 45, receives a final impulsive energization and its armature is attracted. Thus, lever, 43, pulls over the link 65, the hook, 67, of which, acting through arm 60, releases the holding pawl 33, so that the ratchet wheel, 31, starts back toward initial position. In the course of the return traverse of the ratchet wheel, finger 70 trips holding pawl 45' of the secondary ratchet, permitting the latter to return to normal position, cams 80 and 68 leave their coöperating parts, permitting restoration thereof to normal condition, and finally, pin 63, strikes latch 62, and releases the holding pawl of the primary ratchet wheel, 31, so that all parts are restored to normal condition. 75

While I have herein described in some detail a particular embodiment of my invention, it will be apparent to those skilled in the art that many changes in the details of wiring, circuit arrangement, and mechanical construction, might be made without departure from the spirit and scope of the invention and within the scope of the appended claims. 80

What I claim is:

1. In a selective signaling system the combination of a line; a source of current supply therefor; a transmitter for causing signal impulses in the line; a selector apparatus, comprising a primary magnet responsive to signaling impulses in the line, a step-up device actuated thereby, a secondary magnet having an armature, an annunciator, and means operable by a plurality of movements of the secondary armature magnet 100 to initiate the operation of the annunciator; a circuit for said secondary magnet, normally open at two points; switch means associated with the transmitter for closing one of said normally opened points following the transmission of predetermined groups or impulses; and switch means associated with the primary step-up device for closing said circuit at the other point when said step-up device is in predetermined positions. 105

2. In a system of the character described, the combination of a selector, comprising a primary magnet, a step-up device arranged to be advanced step-by-step in equal steps in response to impulses in the primary magnet, switching means associated with said step-up device and arranged to be closed a plurality of times, as said step-up device reaches a plurality of predetermined positions, a secondary electro-magnet, an annunciator, and means for initiating the annunciator operation in response to a plurality of energizations of the secondary magnet; a line circuit for the primary elec- 110

magnet; a source of current supply therefor; a transmitter therein; another circuit for the secondary magnet including the switches of the primary step-up device; and 5 switch means associated with said transmitter to be closed a plurality of times after transmission of predetermined impulse groups from said transmitter, said switching means being likewise included in the 10 secondary magnet circuit.

3. In a system of the character described, the combination of a selector comprising a primary electro-responsive device, a step-up device advanced thereby, a plurality of 15 switching devices associated with said step-up device for successive closure in a plurality of positions of the step-up device, a secondary electro-responsive device, a step-up mechanism actuated thereby, an annun- 20 ciator operable in response to the movement of the said secondary step-up device through a plurality of steps; a transmitter having a switch operable to transmit groups of impulses, and another switch operable for closure between said groups of impulses; a 25 main circuit including said primary electro-responsive device and the first said transmitter switch; and another circuit includ- 30 ing the secondary electro-responsive device, the switch means of the primary step-up device and the second said switch means of the transmitter.

4. In a selective signaling system, the combination of a line, a transmitter adapted 35 for manipulation to transmit impulse groups constituting a plural digit number signal, and a selective device comprising a primary step-up controller advancing step by step in response to the impulse groups, 40 and provided with electric switches successively closable by advances commensurate with digits of the signal appropriate to said selector, a secondary controller comprising an electromagnet, a circuit therefor controlled by each of said switches, and an annun- 45 ciator responsive to a plurality of operations of said secondary controller, equal to the number of digits of such signal.

5. In a selective signaling system, the 50 combination of a line, an impulse transmitter, and a selective apparatus comprising a spring-returnable step-up device, electro-responsive actuating means therefor advancing said step-up device step by step, switches 55 closable by said step-up device at predetermined points, an electro-responsive device connected with said several switches for control by each thereof, a secondary step-up device, controlled by said secondary electro- 60 responsive device, and means cooperating with said parts for restoring the parts to normal position upon actuation of the primary step-up device beyond the range necessary to operate the switches.

6. In a selective signaling system, the

combination of a line, and an impulse transmitter and a selective device comprising a primary ratchet wheel, actuating and holding pawls therefor, a secondary step-up device, actuating and holding means therefor, 70 means connected with the primary step-up device for controlling the actuating means of the secondary step-up device, and mechanical means controlled by the primary device for releasing the holding devices of the primary and secondary step-up devices. 75

7. In a selective signaling system, a line; a source of current supply therefor, a transmitter adapted to transmit in the line impulse groups constituting a plural-digit 80 number-signal; a selector comprising a primary controlling device responsive to line impulses and having a single step-up part arranged to advance and dwell in harmony with the groupings of the signal impulses, 85 a secondary controlling device operable only when the primary step-up part is in predetermined critical positions respectively indicative of successive digits of the appropriate station number, and an annunciator operable in response to a predetermined plurality of operations of the secondary controlling device. 90

8. In a selective signaling system, a line, a source of current supply therefor, a transmitter comprising a switch and a signal wheel, movable means for conditioning the wheel for the transmission of selective plural-digit number signals and at each responsive station a selector, comprising a primary step-up device responsive to the impulses occasioned by the signaling wheel, a secondary controlling device, an annunciator responsive to a plurality of the operations of the secondary responsive device, and 100 means controlled by the primary step-up device and the transmitter whereby the secondary controlling device may perform said series of operations in response to a predetermined number signal only. 110

9. In a selective signaling system, the combination of a line, a source of current supply therefor, a transmitter having a line-controlling switch and a grounding switch adapted to operate the line switch to transmit plural-digit number signals, and to operate the ground switch in the intervals between digits, and a selector device comprising a primary part movable in response to the operations of the line switch, a secondary movable part provided with an actuating magnet arranged in the ground circuit controlled both by the ground switch of the transmitter and by the primary movable part and a working device responsive to a 120 plurality of movements of the secondary movable part. 125

10. In a selective signaling system, the combination of a line, a source of current supply therefor, a transmitter having a line 130

controlling switch and a grounding switch and adapted to operate the line switch to transmit plural-digit number signals and to operate the ground switch in the intervals 5 between digits; and a selector device comprising a primary magnet associated with the line, a step-up device actuated by said magnet, switch means controlled by said step-up device, a secondary magnet, a working part operatively responsive to a given 10 number of operations of said secondary magnet, and ground circuit connections for said secondary magnet controlled by both the transmitter grounding switch and the 15 switch-means associated with the said selector-step-up-device.

11. In a selective signaling system, the combination of a line circuit, a second circuit, means of current supply for said circuits, an impulse transmitter having line 20 controlling switch-means and second-circuit

switch-means, and adapted to operate the line-switch means, to transmit impulse groups and to close the second-circuit switch-means after each impulse group; a 25 selector comprising a magnet responsive to the line impulses, a secondary magnet in the second circuit, a step-up device actuated by the line magnet, switch means controlled thereby controlling the second circuit for 30 the secondary magnet, a working part responsive to a predetermined plurality of operation of the secondary magnet, and means for restoring the parts to normal position controlled by the secondary magnet. 35

In testimony whereof I hereunto set my hand in the presence of two witnesses.
